UNITED STATES PATENT OFFICE

HARRY J. MILLER, OF READING, PENNSYLVANIA

DESIGN FOR A BOX

Application filed July 3, 1931. Serial No. 40,414. Term of patent 3½ years.

To all whom it may concern:

Be it known that I, HARRY J. MILLER, a citizen of the United States, residing at Reading, in the county of Berks and State of Pennsylvania, have invented a new, original, and ornamental design for a Box, of which the following is a specification, reference being had to the accompanying drawing, forming part thereof.

The drawing is a perspective view of a box embodying my design, the indicated zones and bands being formed of pronounced contrasting colors.

What I claim is:

The ornamental design for a box as shown and described.

In testimony whereof, I affix my signature.
HARRY J. MILLER.
